Primary Examiner—Alan P. Douglas*Assistant Examiner*—Robert M. Spear*Attorney, Agent, or Firm*—Owen J. Meegan; Aubrey C. Brine; Donal B. Tobin**[57] CLAIM**

The ornamental design for hood and container, as shown and described.

DESCRIPTION

FIG. 1 is a top plan view of a hood and container showing my new design;

FIG. 2 is a front elevational view thereof;

FIG. 3 is a left side elevational view thereof, the right side elevational view being a mirror image thereof;

FIG. 4 is a rear elevational view thereof; and,

FIG. 5 is a bottom plan view thereof.

The broken line showing of a dispensing nozzle in FIG. 2 is for illustrative purposes only and forms no part of the claimed design.
